UNITED STATES PATENT OFFICE.

WILLIAM HERMAN OPITZ, OF FORT WAYNE, INDIANA.

DISPENSING TANK.

1,422,124.

Specification of Letters Patent. Patented July 11, 1922.

Application filed August 16, 1919. Serial No. 317,920.

To all whom it may concern:

Be it known that I, WILLIAM H. OPITZ, residing at Fort Wayne, in the county of Allen and State of Indiana, a citizen of the 5 United States, have invented or discovered certain new and useful Improvements in Dispensing Tanks, of which improvements the following is a specification.

The invention described herein relates to 10 apparatus for dispensing liquids in different but predetermined quantities and has for its object a construction in which the liquid has a series of outlet openings arranged in different horizontal planes and connected with 15 a common delivery passage. The discharge of liquids through such outlet ports is controlled by a plate being movable across said outlets and having an opening adapted to be brought into register with the outlet ports 20 to permit of the discharge of fluid. The invention is hereinafter more fully described and claimed.

In the accompanying drawings forming a part of this specification, Fig. 1 is a front 25 elevation of the improved dispensing apparatus; Fig. 2 is a side elevation of the same; Figs. 3 and 4 are side and sectional views of the valve or controlling gate; Figs. 5 and 6 are similar views of the valve seat; Fig. 7 is 30 a sectional plan view of the tank and Fig. 8 is a sectional elevation of the tank without the cover, the plane of section being indicated by the line VIII—VIII, in Fig. 7; and Fig. 9 is a sectional detail view illustrating 35 the locking and controlling mechanism and Fig. 10 is a view in elevation of the locking and controlling mechanism.

In the practice of the invention it is preferred to construct the tank A which is provided with a removable cover B, with two dispensing compartments C and D as clearly shown in Figs. 7 and 8, but as each compartment is provided with the similar filling and discharging devices the description will be 45 limited to a single compartment and its filling and dispensing devices.

The liquid to be dispensed is conducted into the compartment or chamber C by a pipe 2, the liquid being supplied from a suitable reservoir not shown, by means of a pump preferably electrically driven, forcing the liquid upwardly through the pipe 2 extending up into the compartment which is also provided with an overflow pipe 4, the 50 upper end of this pipe being located at a level at which the liquid in the compart- ment will stand when the desired quantity has been admitted or fed into the compartment.

This overflow pipe is provided with an 60 adjustable sleeve 4^a to accurately establish the level of the liquid with reference to the several discharge ports or openings. The compartment is provided in one of the walls with a series of outlet ports 5, 6, 7, 8 and 9 65 so located with reference to the level of the liquid when the desired quantity is charged into the tank, that when such port is opened a certain predetermined portion of the liquid will escape through one or the other of the 70 outlet ports dependent upon the quantity to be dispensed. As for example, if the tank is designed to contain 5 gallons of a liquid, the overflow pipe will have its discharge end at such a level that any amount greater than 75 the five gallons will escape therethrough and the upper outlet port 5 will be so located with reference to the discharge end of the overflow pipe that only a predetermined amount of liquid can escape through such 80 outlet port. The other outlet ports are similarly arranged with reference to dispensing similar or greater quantities of the liquid. In the construction shown the several outlet ports are located to discharge 1, 2, 3, 4 and 85 5 gallons.

In order to control the flow of liquid from these outlet ports, a plate-like valve or gate 10 is mounted to move transversely of the line of outlet ports and is provided with 90 an opening 11 therethrough adapted to be brought into registration with one or the other of the outlet ports. While not necessary, it is preferred in order to prevent the 95 accidental escape of the liquid that the outlet ports should be formed in a plate 12 set into a recess in the walls of the tank or compartment. In the construction shown, the outlet ports are arranged with their 100 centers in the arc of a circle and the gate or controlling valve 10 is made in the form of a disc loosely mounted on the pin 13 set in the center of the annulus on which the outlet ports are arranged. The gate or valve 10 is held in position and covered by a hood 105 14 secured by bolts to the side of the tank and provided with a groove 15 into which the liquid will flow from the several ports, the lower end of such groove being connected to a discharge pipe 16. While any suitable 110 means may be employed for shifting the valve or gate 10, it is preferred to operate

the same by means of a pinion 17 mounted upon a shaft 18 and provided with teeth intermeshing with the teeth on the periphery of the gate or valve. In order to indicate 5 the position of the ports or openings through the gate or valve, a second pinion 19 is mounted on the shaft 18 and intermeshes with a pinion 20 loosely mounted on a pin 21 secured in the wall of the tank. This 10 pinion 20 is provided with an indicating finger 22, adapted to move along a scale 23 having marks or indices corresponding with the positions of the several discharge openings from the tank so that when the valve 15 is rotated by its pinion, this finger will indicate which one of the outlet ports or openings 5, 6, etc., in the disc or valve is in register.

It is preferred to employ in connection 20 with the tank a meter which will indicate the total quantity of liquid dispensed from the tank. In the construction shown, a meter 24 of any suitable construction is located on top of the tank and is designed to 25 be operated by a toothed rod 25 having secured to its lower end a float 26 which is guided in its up and down movements by a rod 27 having its ends secured in the bottom and cover of the tank.

30 In order to enable anyone to ascertain the level of the liquid in the tank, a strip of glass 28 is secured in a vertical slot in one of the walls of the tank as shown in Figs. 2, 7 and 8, and alongside of the slot 35 are placed marks corresponding to the maximum height of the liquid and also to the lowest edge of each of the outlet openings. The cover of the tank is provided with an extension 29 forming an open bottomed 40 pocket above the glass strip for the reception of an electric bulb 30, which will illuminate the colored lens 31 in the outer wall of the pocket and also will illuminate the liquid at night showing through the glass strips 28.

45 Suitable means are provided for locking the gate or valve when the opening there-through is out of alinement with the outlets, 5, 6, etc., preferably when the opening through the gate is between the outlets 5 and 50 6. In addition to the primary lock, provision is made for preventing the filling of the tank except when the gate or valve is in such position that no liquid can be dispensed during the filling operation. Desirable forms of locking devices are shown 55 in Figs. 1 and 9. The main lock consists of a pin 32 so mounted in a box 30 carried by the cover or hood 14 that when forced inwardly, the end of the pin will engage a recess 34 in the periphery of the gate or valve 60

10. This pin is shifted and held by a spring 35 and is locked in engagement with the gate or valve by the bolt 36 of a locking mechanism of the Yale or any suitable construction, engaging a notch 37 in the pin, 65 the notch being so located as to be in alinement with the bolt when the pin has been pushed in.

In order to prevent any dispensing of liquid during the charging of the tank, the 70 means employed for such charging is normally locked and cannot be released until the gate or valve 10 is unlocked. In the construction shown an electric motor 38 is provided for operating the charging pump 75 39, and in the circuit of the motor two contact points as 40 and 41 are included, said contacts being arranged in the path of movement of a spring 42 secured on a pin 43 movably mounted in the box 33 as shown in 80 Fig. 9. The periphery of the gate or valve 10 is provided with a recess 44 so located as to be in alinement with the pin, only when the opening in the gate or valve is out of alinement with the dispensing ports 85 5, 6, etc. In the normal or outer position of the pin the spring 42 will be out of contact with one of the contacts as 41 but when the recess 44 is in alinement with the pin 43, it can be shifted sufficiently far to complete the circuit through the motor, at the same time locking the gate or valve. 90

I claim herein as my invention:

1. A dispensing tank having in combination therewith means for charging liquid 95 into the tank, an overflow pipe, a plurality of openings arranged in the arc of a circle and vertically spaced at distances from the inlet to the overflow pipe proportional to the quantities of liquid to be withdrawn from 100 the tank, a rotatably mounted gate or valve provided with a port and means for rotating the gate or valve to bring said port into alinement with any of the spaced openings.

2. A dispensing tank having in combination therewith means for supplying liquid to the tank, an overflow pipe, a plurality of openings vertically spaced at distances from the inlet to the overflow pipe proportional to the quantities of liquid to be withdrawn 110 from the tank, a movable gate or valve having a port, means for shifting the gate or valve to bring said port into alinement with any of the spaced openings and means controlled by the gate or valve for controlling 115 the liquid supplying means.

In testimony whereof, I have hereunto set my hand.

WILLIAM HERMAN OPITZ.
